PAIR OF GOGGLES

George R. Hoffmaster, Esterly, Pa., assignor, by mesne assignments, to The Electric Storage Battery Company, Philadelphia, Pa., a corporation of New Jersey

Application May 21, 1956, Serial No. 41,576

Term of patent 14 years

(Cl. D57—1)

Fig. 1.

Fig. 2.

Fig. 1 is a front perspective view of a pair of goggles, showing my new design; and

Fig. 2 is a rear perspective view thereof, as viewed from the bottom.

I claim:

The ornamental design for a pair of goggles, substantially as shown.
